REFINING PETROLEUM OILS

Henry C. Paulsen, Elizabeth, N. J., assignor to
Standard Oil Development Company, a corpora-
tion of Delaware

Application September 14, 1939, Serial No. 294,800

5 Claims. (Cl. 196—29)

This invention relates to the refining of petroleum oils. The invention is particularly concerned with refining a gasoline and like products, and especially relates to a process and apparatus for treating sulfur-containing oils with sodium plumbite or analogous lead compounds for the purpose of removing sulfur compounds of the character which render the petroleum oil sour. The invention is more particularly directed to an improvement in the so-called "doctor sweetening operation" by which higher quality petroleum products are secured and in which material economies in the process are effected. In accordance with the present invention, the lead mercaptides are converted to disulfides and lead oxide by utilizing hydrogen peroxide in a novel procedure which materially improves the operation.

Mineral oil distillates, as for example, petroleum oil distillates boiling in the kerosene and motor fuel boiling range, contain certain sulfur compounds which impart disagreeable odors to the oil. Various methods have been employed for the removal of these compounds or for the conversion of these disagreeable sulfur compounds to innocuous materials. However, these compounds are usually removed by agitating the oils with an alkaline solution of an alkali metal plumbite such as sodium plumbite which is prepared by dissolving lead oxide in an excess of sodium hydroxide. When the petroleum oil and plumbite solution are mixed, a chemical reaction occurs resulting in the conversion of mercaptans to corresponding lead mercaptides. These mercaptides are then decomposed, usually by the addition of free sulfur, resulting in the lead being precipitated as an insoluble lead sulfide and in the formation of odorless disulfide compounds. This operation known as "sweetening" may be summarized by the following reactions:

This operation is not entirely satisfactory since in order to insure complete removal of the soluble lead compounds from the oil, it is necessary to add a sufficient amount of sulfur, which oftentimes results in the use of an excess of elementary sulfur. The excess sulfur dissolved in the gasoline is very undesirable since it impairs the quality of the gasoline with respect to corrosiveness and anti-knocking properties as measured by a lower octane number. Furthermore, in the usual doctor sweetening operation, certain petroleum oils upon the addition of free sulfur, particularly if an excess be used, will form objectionable polysulfide compounds. If this situation occurs it is necessary to redistill the motor fuel in order to reduce its corrosiveness, to im-

prove its anti-knocking characteristics, and to improve its susceptibility for knock-suppressing agents, as for example, tetraethyl lead.

Various suggestions have been made for overcoming these inherent difficulties resulting from the addition of free sulfur. The suggested methods are more or less cumbersome and not entirely satisfactory from a commercial standpoint. For example, various electrolytic methods have been tried in order to accurately determine the amount of sulfur necessary to just quantitatively precipitate the lead. These methods are not entirely practical since the reaction when using the quantitative amount of sulfur is very slow in reaching completion which decreases the through-puts and equipment capacities.

I have now discovered a process by which sour oils may be readily treated in the usual manner with an alkaline solution of sodium plumbite or doctor solution and the resulting soluble lead mercaptides completely converted in an efficient manner. In accordance with my invention, these soluble lead mercaptides are converted to lead oxide and lead sulfide by the addition of hydrogen peroxide to the oil containing litharge, thus insuring that the sulfur content of the oil will not be increased and that no undesirable sulfur polymers will be formed. The process of my invention may be demonstrated by the following reactions:

My invention necessarily results in the production of a higher quality oil completely free of corrosive sulfur and having high anti-knocking characteristics as well as having a high susceptibility for knock suppressing agents. Possible re-running of the treated oil for the removal of undesirable sulfur polymers is eliminated. Furthermore, my process eliminates the regeneration of doctor solution stage since the lead from the hydrogen peroxide treated oil containing litharge is removed as lead mono-oxide by washing with sodium hydroxide and used as fresh doctor solution.

The process of my invention may be readily understood by reference to the attached drawing illustrating one modification of the same. For purposes of description, the feed oil is taken to be a mercaptan containing petroleum naphtha boiling in the motor fuel boiling range. The sour gasoline containing mercaptans is introduced into the sweetening system by means of feed line 1. A solution of sodium plumbite is introduced into the sweetening system by means of line 4 and is mixed with the sour gasoline in contacting pump 2. The mixture in an initial stage passes through valve 3, mixer 31 and line 5

into settling drum 6, wherein separation of the spent doctor solution from the leaded gasoline containing lead mercaptides occurs. In the initial stage the mercaptan compounds contained in the oil are converted to oil-soluble lead mercaptides and the spent doctor solution layer segregated from the leaded oil. The leaded gasoline containing lead mercaptides is withdrawn from settling drum 6 by means of line 7 and in a secondary stage mixed with hydrogen peroxide which is introduced by means of line 12 and contacting pump 10, the mixture withdrawn from contacting pump 10, by means of line 11 and introduced into settling drum 13, wherein separation of the spent aqueous hydrogen peroxide solution from the gasoline containing suspended lead oxide occurs. In the secondary stage, the lead mercaptides are reacted with hydrogen peroxide under conditions to form an oil layer containing lead oxide and a spent aqueous solution of hydrogen peroxide. The spent aqueous peroxide solution is withdrawn from settling drum 13 by means of a liquid level control valve 15 and line 16. The oil containing suspended lead oxide is withdrawn from settling drum 13 by means of line 14, and in a tertiary stage contacted with spent doctor solution from said initial stage under conditions whereby a treated substantially lead-free oil phase containing disulfides and a regenerated doctor solution phase are formed. The oil withdrawn by means of line 14 is passed through contacting pump 17 wherein it is mixed with spent doctor solution withdrawn from settler 6 by means of line 9. This mixture is withdrawn from contacting pump 17 by means of line 18 and introduced into settling drum 19. The regenerated doctor solution separates from the sweetened gasoline in settling drum 19 and is withdrawn from settling drum 19 through valve 21 and then passed into doctor solution storage 29 by means of line 22. The doctor solution is withdrawn from doctor solution storage 29 by means of line 4 and mixed with fresh unsweetened gasoline in contacting pump 2. Fresh doctor solution may be introduced in the system by means of line 32. The sweetened gasoline substantially free of lead oxide is withdrawn from settling drum 19 by means of line 23 and passed into mixing column 24 along with water which is introduced by means of line 23. The water-gasoline mixture is withdrawn from mixing column 24 by means of line 25 and passed into settling drum 26 in which the added water is separated from the sweetened washed gasoline. The water is withdrawn from settling drum 26 by means of a liquid level control valve 27 and line 28, while the finished sweetened gasoline is withdrawn from settling drum 26 by means of line 30 and passed to finished gasoline storage. Liquid level control valves 8, 15, 21 and 27 control the level of the heavier layers which are withdrawn from the bottom of the respective settlers. It is to be understood that any desirable mixing, heating, cooling, or distributing means may be employed.

The process of the present invention may widely vary. Although elevated temperatures and pressures may be employed, it is preferred to contact the gasoline with the doctor solution at ordinary temperatures and pressures. The amount of hydrogen peroxide introduced should be sufficient to completely convert all soluble lead compounds to lead oxides. In general, it is preferred to use aqueous peroxide solutions of 1 to 20% peroxide concentration, preferably having a

5 peroxide concentration of from 5 to 10%. When using aqueous solutions of peroxides of these concentrations, it is sufficient to contact the lead mercaptide containing oil with from about 2 to 10% of aqueous peroxide solution.

10 The process of the present invention is not to be limited by any theory or mode of operation, but only in and by the following claims in which it is desired to claim all novelty in so far as the prior art permits.

I claim:

1. Process for converting mercaptan compounds contained in the petroleum oil to disulfide compounds, comprising contacting said petroleum oil in an initial stage with a sodium plumbite solution under conditions to convert the mercaptan compounds to corresponding soluble lead mercaptides, separating the spent sodium plumbite solution from the treated oil containing the soluble lead mercaptides, passing the treated oil fraction into a secondary stage and contacting the same in said secondary stage with hydrogen peroxide under conditions to convert the lead mercaptides to lead oxide and disulfide compounds, whereby a water layer is formed in said secondary stage, separating the water from the treated oil, passing the treated oil containing soluble lead disulfides and the lead oxide to a tertiary stage and contacting the treated oil in said tertiary stage with the spent alkali metal plumbite solution removed from said initial stage whereby the lead oxide is completely removed from said treated oil.

2. Process as defined by claim 1, in which said alkali metal plumbite solution is a sodium plumbite solution.

3. Process as defined by claim 1, in which the spent alkali metal plumbite solution containing the lead oxide is removed from said tertiary stage and recycled to said initial stage.

4. Continuous process for converting mercaptan compounds contained in a petroleum oil to disulfide compounds which comprises passing said oil continuously through an initial, a secondary, and a tertiary stage, contacting said oil in said initial stage with a sodium plumbite solution under conditions to convert the mercaptan compounds to corresponding lead mercaptides, separating the spent alkali metal plumbite solution and the treated oil and withdrawing the said spent alkali metal plumbite solution and the said oil from said initial stage, contacting the treated oil removed from said initial stage in said secondary stage with hydrogen peroxide under conditions to convert the lead mercaptides to lead oxide and disulfide compounds, whereby a water layer is formed, separating the water layer from the treated oil containing lead oxide and withdrawing the said water layer and the said treated oil containing lead oxide from said secondary stage, contacting the treated oil withdrawn from said secondary stage in said tertiary stage with the spent alkali metal plumbite solution withdrawn from the initial stage, whereby a treated oil layer completely free of lead oxide and a spent alkali metal plumbite solution layer containing the lead oxide are formed, separating the layers and withdrawing the said treated oil layer and the said spent alkali metal plumbite solution from said tertiary zone.

5. Process as defined by claim 4, in which the spent alkali metal plumbite solution containing the lead oxide is removed from said tertiary stage and recycled to said initial stage.

HENRY C. PAULSEN.
